WINTHROP T. SCARRITT, OF UTICA, NEW YORK, ASSIGNOR TO THE PRATT CHUCK CO., OF FRANKFORT, NEW YORK, A CORPORATION OF NEW YORK

TUBING

Application filed December 11, 1929. Serial No. 413,412.

This invention relates to tubing and method of making the same.

It is among the objects of the present invention to provide a rigid metallic tubing formed by the connection of spiral interlocking helixes.

A further object of the present invention is to provide a novel method for forming a spiral tubing.

10 In connection with the present invention a rigid tubing or pipe is formed by joining adjacent edges of adjacent helixes by interlocking, the adjacent edges being provided with shoulders which abut the juncture of 15 the edges to prevent telescopic movement therebetween.

The invention further contemplates the use of solder in the interlocked joint whereby the same will be held rigid and gas and water-

20 proof.

The object of the present invention includes the provision of a novel, simple tubing, which has maximum strength as compared with the type of material used, and also the 25 provision of a novel method of forming rigid tubing.

Other objects of the present invention will be apparent from a consideration of the following specification taken in conjunction 30 with the accompanying drawings, in which

Figure 1 is a side elevation of a rigid metallic pipe or tubing formed in accordance with the present invention;

Fig. 2 is a sectional view taken on the line 35 2—2 of Fig. 1, and showing the interlocking connection between the edges of the helixes before rolling, and

Fig. 3 is a similar view showing the pipe in rolled finished form.

40 Referring more particularly to the drawings, it will be seen that the tubing or pipe 10 is formed by the connection of adjacent edges of a spiral strip of material 11. As seen in Fig. 2, one edge of the strip 11 is inwardly bent as at 12, to form a substantially transverse abutting wall and the edge extends outwardly therefrom to form the outer wall 13, which is return bent, as at 14, to provide an inner flange 15. The opposite edge 50 of the tubing and therefore the edge next ad-

jaacent the one hereinbefore described, includes an outwardly turned shoulder 16, the edge extending inwardly therefrom to form the inner wall 17, which is return bent, as at 18, to provide an outer interlocking flange 55 19.

The method steps of forming the tubing include the spiral bending of the tubing, the return bending of the edges to provide the interlocking portions, together with the abutting shoulders, and the subsequent interlocking of the edges and rolling thereof, to provide a rigid union therebetween. It will be understood that the tubing is preferably formed in a machine which carries on the 60 method steps automatically. However, the machine forms no part of the present invention, and the method steps are clearly differentiated one from another.

65 In some instances it may be desirable to reinforce the juncture to provide for gas and water tightness thereof by the inclusion of solder. As shown in Fig. 2, a strip or bead of solder 20 may be provided between the flanges 15 and 19. Due to the heat of rolling or by applied heat after the rolling operation, the solder 20 spreads between the flanges 15 and 19, to form the tight juncture shown in Fig. 3. It will be understood that 70 the solder is not an indispensable portion of 75 the present invention and the spirit and scope of the appended claims is not limited by the inclusion thereof.

75 From the foregoing it will be seen that applicant has provided a novel and improved rigid tubing and method of making the same. In connection with the strength of the tubing thus formed, it will be seen that by the spiral arrangement, both longitudinal and transverse stresses are carried to the juncture at an angle other than an angle of 180 degrees. Thus the strains affect the juncture in tangential relation so that contracted or expanded strains will not effect a rupture 80 of the juncture.

85 It will further be seen that the present invention provides novel means for associating the edges of adjacent helixes of a spiral. The interlocking formation herein shown provides for a shoulder on each side 90 95 100

of the juncture, whereby telescoping the juncture is prevented, and in addition thereto, the rolled shoulder may provide for expansion and contraction while, at the same time, 5 insuring a rigid tubing.

It will be seen that the method steps employed provide for the formation of the tubing in large quantity production, it being understood that the formation of the tubing is 10 substantially continuous, and that the machine may be arranged to cut desired lengths of tubing by a simple adjustment thereof.

From the foregoing it will be understood that the present invention is not specifically confined to the detail structure herein presented nor to the specific method steps herein enumerated; thus numerous changes, modifications, and the full use of equivalents may be utilized in the present invention without departing from the spirit or scope thereof.

What is claimed is:

1. A tubing formed of a single piece of helically formed material, with one side bent inwardly to form a transverse shoulder 25 adjacent one edge and with its other side bent outwardly to form a transverse shoulder adjacent its other edge, return bent portions beyond the shoulders, the return bent portions of adjacent helices interlocking, with the shoulder adjacent each return bent portion engaging a return bent portion on an adjacent helix to hold the return bent portions in position relatively to each other and support the tubing under longitudinal and 30 transverse stresses.

2. A tubing formed of a single piece of helically formed material, with one side bent inwardly to form a transverse shoulder adjacent one edge and with its other side bent outwardly to form a transverse shoulder adjacent its other edge and with return bent portions beyond the shoulders, the return bent portions of adjacent helices interlocking, with the shoulder adjacent each return bent portion engaging a return bent portion on an adjacent helix to hold the return bent portions in position relatively to each other and support the tubing under longitudinal and transverse stresses, and a 35 strip of solder between the interlocking return bent portions of adjacent helices.

3. A tubing formed of a single piece of helically formed material with one side bent outwardly and inwardly to form a transverse shoulder, the material beyond the shoulder extending longitudinally of the tubing and then outwardly and being return bent, the other side of the material being bent inwardly and outwardly to form a shoulder, the material beyond the last mentioned shoulder extending longitudinally of the tubing and then inwardly and being return bent, the return-bent portions of adjacent helices interlocking with the shoulder adjacent each 40 return-bent portion engaging a return-bent

portion of an adjacent helix to hold the return-bent portions in position and yielding relatively to the body of the tubing for supporting the tubing under longitudinal and transverse pressure.
